SUCTION NOZZLE

Anders Eriksson-Jons, Stockholm, Sweden, assignor to Electrolux Corporation, Dover, Del., a corporation of Delaware

Application June 26, 1936, Serial No. 87,385
In Switzerland July 2, 1935

2 Claims. (Cl. 15—155)

My invention relates to suction nozzles for use in connection with a vacuum cleaner and particularly to duplex nozzles provided with openings of different sizes which may be selectively connected to the source of suction. When the larger opening is in use it will cover a larger surface, thereby increasing the speed of cleaning. However, if a concentrated suction is desired in order to remove dirt which the larger opening will not pick up, the smaller opening may be brought into use.

The objects and advantages of my invention will be apparent from the following description considered in connection with the accompanying drawing which forms part of this specification, and of which:—

Fig. 1 is a cross-sectional view showing a preferred embodiment of my invention; and

Fig. 2 is a cross-sectional view taken on the line 2—2 of Fig. 1.

Referring to the figures reference character 10 designates a hollow conduit adapted to be connected to a source of suction and to act as a handle for moving the nozzle over the surface to be cleaned. The nozzle includes a cylindrical portion 11 adapted to receive conduit 10 and formed integral with an elongated hollow body portion 12. The lower part of portion 12 forms an elongated suction opening 13. The upper central part of portion 12 is formed as an inclined flat wall 14 formed with an opening 15 adjacent the lower end thereof and in alignment with the interior of cylindrical portion 11. The upper part 16 of wall 14 is solid.

Slidably mounted within openings formed in hollow portion 13 is a handle member 17. Secured to handle member 17 within the hollow portion 13 is a small suction nozzle member 18 having an inclined upper face adapted to slide on the inner side of flat portion 14. A spring pressed detent 19 is provided for retaining handle member 17 in either of two extreme positions.

With the parts in the position shown in Fig. 1, the interior of small nozzle member 18 is in alignment with the opening 15 in wall 14, and hence with the interior of the cylindrical part 11.

Consequently, all of the air drawn through the conduit 10 will pass through the small suction opening 20 in nozzle member 18, thus providing a concentrated suction.

In the event that it is desired to employ the

elongated suction opening 13, handle member 17 is slid to the right as viewed in Fig. 1, thus moving nozzle member 18 in the same manner. In this position the nozzle 18 is in alignment with the solid portion 16 of the flat wall and is hence removed from communication with the interior of cylindrical member 11. Due to the fact that wall 14 is inclined, this movement to the right of nozzle 18 also results in its moving up a distance sufficient so that its lower end is above the elongated opening 13. This elongated opening is now in direct communication with the interior of cylindrical portion 11, whereby the suction will be applied to the entire elongated opening.

While I have shown and described one more or less specific embodiment of my invention it is to be understood that this has been done for purpose of illustration only, and that the scope of the invention is not to be limited thereby, but is to be determined by the appended claims viewed in the light of the prior art.

What I claim is:—

1. A suction nozzle including a hollow body portion, defining a large suction opening and a hollow integral portion adapted to be connected to a source of suction, said nozzle being formed with a port between said portions, a small tubular nozzle member slidably mounted within said body portion, and means for sliding said member to an operative position in alignment with said port, whereby all air passes through said member, and to an inoperative position out of alignment with said port.

2. A suction nozzle including a hollow body portion, defining a large suction opening and a hollow integral portion adapted to be connected to a source of suction, said nozzle being formed with a flat wall inclined with respect to the plane of said large section opening, said wall being formed at its lower end with a port connecting said portions, a small tubular nozzle member mounted within said body portion so as to be slidably along said inclined wall, and means for sliding said member to an operative position in alignment with said port, whereby all air passes through said member, and with the lower end of said member projecting through said elongated opening and to an inoperative position out of alignment with said port and with said member retracted within said body portion.

ANDERS ERIKSSON-JONS.
